VAPOR ELECTRIC DEVICE

William E. Pakala, Forest Hills, Pa., and Herbert A. Rose, Seattle, Wash., assignors to Westinghouse Electric Corporation, East Pittsburgh, Pa., a corporation of Pennsylvania

Application March 26, 1949, Serial No. 83,612

4 Claims. (Cl. 250—27.5)

1

Our invention relates to a vapor-electric device and particularly to a vapor-electric valve capable of withstanding rapidly applied potentials between the anode and cathode.

It is frequently desirable to use vapor-electric valves to convert direct current to alternating current or alternating current of one frequency to alternating current of another frequency and while it is substantially impossible to terminate an electric arc in a vapor-electric device without reversing the polarity applied to the device, it is now customary to provide oscillator circuits which momentarily reverse the potential or stop the current flow so that any desired frequency of output may be attained either from direct current or from alternating current of any frequency. However, considerable difficulty has been experienced by reignition of the arc in the device upon the application of potential before the ionization has disappeared in the valves.

According to our invention, we provide a valve having, in addition to the normal control grids present in conversion tubes, at least a pair of deionizing grids one of which is placed in closely spaced proximity to the control grid and the other close to the anode surface so that the ionization produced by the arc in the valve will be rapidly dissipated so that the appearance of potential between the anode and cathode will find the ions at the anode and cathode so thoroughly dissipated that spontaneous ignition of a cathode spot at either electrode is substantially prevented.

It is accordingly an object of our invention to provide a vapor-electric valve having a high deionization rate.

It is a further object of our invention to provide an electric valve through which a potential may be rapidly reapplied after a conducting interval.

It is a further object of our invention to provide a vapor-electric valve having deionizing grids in proximity to each of the major electrodes in the device.

Other objects and advantages of our invention will be apparent from the following detailed description taken in conjunction with the accompanying drawing, in which the figure is a sectional elevation of a vapor-electric valve embodying our invention.

In the exemplary embodiment of our invention, the vapor-electric valve comprises a metallic container 1 having a cooling means such as a water jacket 2 applied to the exterior surface of at least a portion of the container 1 to provide

2

a cooled condensing surface 3 on the interior of the container wall. A pool 4 of cathode material, such as mercury, is retained in the bottom portion of the container 1 and the anode 5, usually of graphite, is supported in spaced insulated relation by means of an anode stem 6 mounted in a lead-in bushing 7 attached to the top header 8 of the container 1.

A make-alive or ignitor 10 is provided in contact with the cathode pool 4 for initiating a cathode spot at desired intervals on the cathode. The anode 5 is surrounded on the sides and the back by an anode shield 11 supported from the top header 8 of the container 1 by means of a plurality of insulating bushings 12. The open end of the anode shield 11 is provided with a control electrode 13 which is closely spaced adjacent the operating face 14 of the anode 5. Control potential is applied to the grid 13 from any suitable source through a lead-in connection 15 usually provided in the header 8 and connected to the anode shield 11.

In order to deionize the space immediately adjacent the control electrode 13, a deionizing grid 16 is placed in proximity to the controller grid 13 and is usually supported by a metallic cylinder 17 also attached in insulated relation to the container, preferably by means of the same insulating bushings 12 that support the anode shield 11. If desired, potentials of various kinds may also be applied to the deionizing grid by means of a lead-in bushing 18 attached in insulated relation to the container header 8.

A second deionizing grid 20 was placed immediately above the surface of the cathode pool 4 and is preferably supported by means of rods or strips 21 attached to the cylinder 17 supporting the first-mentioned deionizing grid 16. The rods or strips 21 are used so that the space between the deionizing grids 16 and 20 is open to the condensing surface 3 or cooled side wall of the container 1 so vapor between the deionizing grids may have free access to the condensing surface 3 and not only reduce the vapor pressure but materially de-energize the space between the grids 16 and 20. The deionizing grid 20 adjacent the cathode surface is provided with a plurality of openings 22 which is directed away from the line of passage between the anode 5 and the cathode 4 so that the vapor and any droplets thrown off from the cathode surface will be deflected away from the anode 5 and toward the condensing surfaces 3.

In the operation of the device according to our invention, a cathode spot will be established at the beginning of the conducting interval and will

be maintained by a suitable potential applied usually to the deionizing grid 20 which acts then as a keep-alive electrode for a predetermined interval. Control potentials of the desired frequency are applied to the control electrode 13 so that current then can pick up from the main anode 5 to the cathode 4 and will flow as long as the current conditions of the circuit permit. When the circuit conditions terminate current flow the deionizing grids 16 and 20 will rapidly reduce the ionization adjacent the anode 5 or control electrode 13 and the cathode surface so that the reapplication of a potential between the anode 5 and cathode 4 will not automatically restrike but must await the control action of the control grid 13.

We have found that with a spacing of the order of one-half inch between the deionizing grid and the cathode surface, that the ionization will be reduced below the danger value in a time of the order of 65 micro-seconds and a tube with these characteristics will work at a frequency of approximately 3,000 cycles without premature restriking because of the ionization present.

While for purposes of illustration, we have shown a specific embodiment of our invention and described the same to the best of our present ability, we wish it to be understood that this is illustrative only and that many changes and modifications can be made therein without departing from the true spirit of our invention or the scope of the appended claims.

We claim as our invention:

1. A vapor-electric discharge device comprising a container, means for cooling the walls of said container, a cathode pool in said container, an anode supported in spaced insulated relation to said cathode pool, a shield enclosing the sides and back of said anode, a control grid adjacent the face of the anode, a deionizing grid adjacent said control grid, a second deionizing grid adjacent the cathode pool, the grid passages of said cathode grid being inclined relative to the direction between anode and cathode.

2. A vapor-electric device comprising a container, a cathode pool in said container, an anode

spaced from said pool, means for cooling the side walls of said container to provide a condensing surface, a cathode grid closely spaced with respect to the surface of the cathode pool, an anode grid closely spaced with respect to the surface of the anode, the space between said anode and cathode grid being substantially greater than the distance between said cathode and said grid, said space being substantially open to the condensing surface.

3. A vapor electric valve for operation at high frequency comprising a container, a vaporizable cathode in said container, an anode in spaced insulated relation in said container, a control grid closely spaced from said anode, a pair of deionizing grids between said control grid and said cathode, one of said deionizing grids being closely spaced with respect to said control grid, the other deionizing grid being closely spaced with respect to the cathode surface, metallic supports between said deionizing grids, the surface area of said supports being small in respect to the lateral area between said deionizing grids.

4. A high-frequency vapor-electric device comprising a container, means cooling the side walls of said container, a pool of cathode material in said container, an anode in spaced insulated relation to said pool, a control grid adjacent the face of the anode, a pair of deionizing grids interposed between said control grid and the surface of the pool, said pair of deionizing grids being widely spaced from each other, said deionizing grid adjacent the cathode being spaced from the pool surface a distance of the order of one-half inch.
